[57] CLAIM

The ornamental design for a multi-media portable computer, as shown and described.

DESCRIPTION

FIG. 1 is a perspective view of the personal computer with the cover fully opened;

FIG. 2 is a perspective view of the personal computer with the cover closed;

FIG. 3 is a perspective view thereof with the cover open and a camera extracted;

FIG. 4 is a rear perspective view thereof with the cover open;

FIG. 5 is a front elevational view thereof with the cover opened;

FIG. 6 is a rear elevational view thereof with the cover opened;

FIG. 7 is a top plan view thereof with the cover opened;

FIG. 8 is a bottom plan view thereof with the cover opened;

FIG. 9 is a left side elevational view thereof with the cover opened;

FIG. 10 is a right side elevational view thereof with the cover opened;

FIG. 11 is a front elevational view thereof with the cover closed;

FIG. 12 is a rear elevational view thereof with the cover closed;

FIG. 13 is a top plan view thereof with the cover closed;

FIG. 14 is a bottom plan view thereof with the cover closed;

FIG. 15 is a left side elevational view thereof with the cover closed; and,

FIG. 16 is a right side elevational view thereof with the cover closed.
